UNITED STATES PATENT OFFICE.

PATRICK KILLPATRICK, OF HURON, SOUTH DAKOTA.

RESTAURANT-SERVICE.

992,672.

Specification of Letters Patent. Patented May 16, 1911.

Application filed January 25, 1911. Serial No. 604,525.

To all whom it may concern:

Be it known that I, PATRICK KILLPATRICK, a citizen of the United States, and a resident of Huron, in the county of Beadle, 5 State of South Dakota, have invented a new and useful Improvement in Restaurant Services, of which the following is a specification.

My invention is an improvement in res- 10 taurant service, and consists in certain novel constructions and combinations of parts hereinafter described and claimed.

The object of the invention is to provide an improvement in devices of the character 15 specified, wherein a means is provided for serving a number of tables automatically, and by means of which the orders may be conveyed to the individual tables, and the empty dishes returned to the kitchen.

20 Referring to the drawings forming a part hereof: Figure 1 is a diagrammatic side view of the improvement; Fig. 2 is a bottom plan view of the track; Fig. 3 is a perspective view of the carriage and a portion of 25 the tracks; and Fig. 4 is a side view of the connection between the carriage and its operating means.

The present embodiment of the invention is arranged in the dining room of a res- 30 taurant or hotel, and comprises a track composed of spaced rails 1 and 2, which are preferably of dumb bell cross section, as shown in Fig. 3. The rails are preferably suspended from the ceiling 3 of the room by 35 means of hangers 4 arranged at suitable intervals to properly support the track, and the rails are preferably connected at spaced intervals by cross ties 5, to whose centers the hangers 4 are connected. In order that as 40 many tables as possible may be served, a plurality of tracks is preferably provided which may be arranged as shown in Fig. 2, or in any other suitable manner. As shown in the said figure, the track consists of a 45 main track designated generally by the reference character A, and a plurality of branch tracks designated generally by the reference characters B and C and interposed in the length of the main track. The main track is arranged at the longitudinal center 50 of the room, and the branch tracks are arranged alongside each other and converge toward their ends. The carriage is shunted from the main track to the branches by 55 means of turntables D, one of which is arranged at each of the converging ends. The

turn table may be of any suitable construction, that shown comprising a circular plate 6 rotatably mounted intermediate the adjacent ends of the main and branch tracks 60 by means of hanger rods 7, which connect the said plate to a second plate 8 pivoted at 9 to the ceiling of the room.

The lower face of the plate 6 is provided with spaced rails 10 and 11 connected by 65 cross ties 12, and the said rails are adapted to register with the ends of the rails 1 and 2 of the main and branch tracks. The tables D are turned by means of the carriage, which will now be described. The said carriage comprises a pair of frame bars of 70 similar shape and construction, each of which consists of a body portion 13, having at its center a journal pin 14 on which is journaled a grooved wheel 15 running on the adjacent rail 1 or 2. Each of the frame bars is provided with a depending portion 16 at each end, which extends to the level of the lower face of the rail, and is then bent inwardly to form a journal pin 17 and 80 thence is bent inwardly, downwardly and laterally at 18 to a connection with one arm 19 extending from a socket 20. A grooved wheel 21 is journaled on each of the journal pins 17 and engages the under face of the adjacent rail, and the socket 20 is at the vertical center of the carriage. The socket is provided with four arms 19 so that both 85 frame bars are connected therewith. The carriage is held firmly on the track by means of the wheels 15 and 21, so that it cannot 90 become derailed, yet the carriage does not interfere with the cross ties 5 or 12 or the hanger rails 4 or 7 which are connected to the centers of the respective ties.

95 A tray is supplied from the carriage, the said tray comprising a lower portion 22 for receiving the orders, and an upper portion 23 for the empty dishes. The said trays are secured to a rod 24 whose upper end is passed through the socket 19, and is engaged by a collar 25 above the socket. The collar is pinned to the rod by a pin 26 to prevent disengagement thereof.

100 In the operation of the device the orders are placed on the plate or tray 22, which, as shown in Fig. 1, is provided with side flanges 27, and is also provided with an elevated rail 28 at the forward end of the tray. The rail is arranged at the front and is elevated to prevent the dishes moving forward 110 from inertia, should the carriage be checked

too suddenly. The tables 29 are arranged at suitable intervals below the tracks B and C, and the carriage passes out of the kitchen on the main track A. The turn table adjacent to the kitchen is turned with its rails in register with those of the main track and the carriage is run onto the said rails. The carriage is then turned by grasping the tray 23, which may be omitted if desired and replaced by a turning handle. The turning of the tray turns the carriage and also the turn table, and when the rails of the table are in register with the rails of the track B or C, as the case may be, the carriage is run off the turn table onto the said track. When a table is reached the orders are removed and the carriage is moved to the next table. When the tables of the track on which is the carriage, as, for instance, B, are served, the carriage is run onto the turn table at the opposite end of the track, and the table is turned until its rails register with those of track C. The carriage is then run onto the said track C and the tables thereof are served. The carriage may return to track A direct from track C or by way of track B, as may be desired.

The carriage may be moved by any suitable means, and the tray 22 is held in place by a plurality of collars 29, one of which is arranged above and one below the bottom of the tray. Each collar is annularly flanged at the end adjacent to the tray, as shown at 30, and the collar is held in place on the rod by a pin 31. A washer 32 encircles the rod between the flange 30 of each collar and the tray. The tray is thus held firmly in place, but may be removed if necessary for any purpose.

It will be evident that the tracks may be arranged in many different ways, and each track may serve a plurality of lines of tables, if desired, one line being arranged on each side of the track.

The device is inexpensive and may be installed without any changes in the room. The device is also easily operated, not liable to get out of order, and will do the work of a great number of waiters.

I claim:

1. In combination, a main track and a plurality of branch tracks interposed in the length of the main track, hangers for suspending the tracks, the branch tracks converging at their ends, a pivotally mounted turn table at the ends of the tracks and between the main track and the adjacent converging ends of the branch tracks, a carriage movable on the tracks, a rod depending from the carriage, and a tray secured to the rod.

2. In combination, a main track and a plurality of branch tracks interposed in the length of the main track, hangers for suspending the tracks, the branch tracks con-

verging at their ends, a pivotally mounted turn table at the ends of the tracks and between the main track and the adjacent converging ends of the branch tracks, a carriage movable on the tracks, and a tray depending from the carriage. 70

3. In a device of the character specified, the combination of spaced rails, cross ties connecting the rails, hangers connected with the cross ties, a carriage comprising spaced frame bars one above each rail, a grooved wheel journaled on each bar at its center and running on the rail, each bar having a portion depending below the rail at each end and bent beneath the rail and laterally inward and downward to the vertical center of the carriage, a grooved wheel on each of the said portions beneath the rail and engaging the under face thereof, a socket connecting the said portions of both frame bars beneath the rails, a rod in the socket, and a tray on the rod. 75 80 85

4. In a device of the character specified, the combination of spaced rails, cross ties connecting the rails, hangers connected with the cross ties, a carriage comprising spaced frame bars one above each rail, a grooved wheel journaled on each bar at its center and running on the rail, each bar having a portion depending below the rail at each end and bent beneath the rail and laterally inward and downward to the vertical center of the carriage, a grooved wheel on each of the said portions beneath the rail and engaging the under face thereof, a socket connecting the said portions of both frame bars beneath the rails, a rod in the socket, and a tray on the rod. 90 95 100

5. In a device of the character specified, the combination of spaced rails, cross ties connecting the rails, hangers connected with the cross ties, a carriage comprising spaced frame bars one above each rail, a grooved wheel journaled on each bar at its center and running on the rail, each bar having a portion depending below the rail at each end and bent beneath the rail and laterally inward and downward to the vertical center of the carriage, a grooved wheel on each of the said portions beneath the rail and engaging the under face thereof, a connection between the said portions below the rails, and a tray carried by the connection. 105 110 115

6. In a device of the character specified, the combination of spaced rails, cross ties connecting the rails, hangers connected with the cross ties, a carriage comprising spaced frame bars one above each rail, a grooved wheel journaled on each bar at its center and running on the rail, each bar having a portion depending below the rail at each end provided with a journal pin beneath the rail, a grooved wheel on each pin engaging the under face of the rail, a connection between the inner ends of the said pins, and a tray supported by the connection. 120 125 130

7. In a device of the character specified, the combination of spaced rails, cross ties connecting the rails, hangers connected with the cross ties, a carriage comprising spaced frame bars one above each rail, a grooved wheel journaled on each bar at its center and running on the rail, each bar having a depending portion at each end provided

with a journal pin beneath the rail, a grooved wheel on each pin engaging the under face of the rail, and a tray depending from the said pins below the rails.
